Primary Examiner — Jennifer Rivard*Assistant Examiner* — Catherine S Posthauer(74) *Attorney, Agent, or Firm* — Maschoff Brennan; Paul G. Johnson(57) **CLAIM**

The ornamental design for a lid, as shown and described.

DESCRIPTION

FIG. 1 is a top perspective view of a lid, showing the lid in position of use with an example bottle;

FIG. 2 is a top perspective view thereof, with the example bottle removed for clarity of details;

FIG. 3 is a bottom perspective view thereof;

FIG. 4 is a front view of the lid, with the left side view, right side view, and rear view being mirror images thereof;

FIG. 5 is a top view thereof; and,

FIG. 6 is a bottom view thereof.

The dot-dash broken lines represent the bounds of the claimed design and form no part thereof. The dashed broken lines are shown for the purpose of illustrating environmental structure and parts of the article that form no part of the claimed design.

1 Claim, 6 Drawing Sheets(58) **Field of Classification Search**
